UNITED STATES PATENT OFFICE.

ZACHARIAH C. PHILLIPS, OF ALLEGHENY, PENNSYLVANIA.

BORING-MACHINE.

SPECIFICATION forming part of Letters Patent No. 296,053, dated April 1, 1884.

Application filed November 28, 1883. (Model.)

To all whom it may concern:

Be it known that I, ZACHARIAH C. PHILLIPS, of Allegheny, in the county of Allegheny and State of Pennsylvania, have invented 55 a new and useful Improvement in Boring-Machines; and I do hereby declare the following to be a full, clear, and exact description thereof.

My invention relates to an improvement in 10 boring-machines; and it consists in an improved boring-machine which is automatically self-withdrawing, and in which augers having shanks of any length may be used.

I will now describe my invention so that 15 others skilled in the art may manufacture and use the same, reference being had to the accompanying drawings, forming part of this specification, in which—

Figure 1 is a front elevation of my improved 20 apparatus. Fig. 2 is a side elevation of the adjusting-quadrant. Fig. 3 is a plan view of the miter-wheels and shafts, and Fig. 4 is a detached view of the pieces forming the extension-handles.

Like letters of reference indicate like parts 25 wherever they occur.

The essential parts of my improved boring apparatus are a vertical hollow auger-shaft, and a horizontal crank-shaft, connected by 30 skew miter-wheels or by other devices, a rack, a pinion mounted on the crank-shaft, a clutch for engaging the pinion with the shaft, and devices for throwing the clutch in and out of gear with the pinion, as hereinafter more fully 35 appears; also in the construction and arrangement of the parts of the apparatus.

In the drawings, *a* represents the bed-frame, at one end of which is pivoted the vertical standards or frame *b b'*, which are held at the 40 desired angle with the frame *a* by means of the quadrant *c*, the lower end of which is pivoted to the frame *a*, while the other end passes through a slot in the plate *b²* on the frame *b*, so that the frame *b* may be held by the key *d*, which is wedge-shaped, and is placed in the 45 slot below the quadrant.

Situated between the standards *b b'* is the sliding frame *e*, in which is mounted the vertical hollow rotating auger-shaft *f*, in which, 50 at the collars *g*, are the set-screws or bolts *h*, or other device for seizing the auger-shank when it is inserted in the shaft.

In order that the apparatus may be used with augers having shanks of different lengths, the shaft is hollow throughout its length, and the horizontal crank-shaft *i* is situated not over the shaft *f*, but at one side thereof, to permit the passage of the shank of the auger. This crank-shaft *i* is mounted on bearings *k*, 55 extending from the sliding frame *e*, and the two shafts are connected by the skew miter-wheels *m n*, the wheel *m* being keyed to the shaft *f*, and the wheel *n* being attached to the shaft *i* by a feather or spline; or, as shown in the drawings, by a pin, *n'*, passing through a 60 longitudinal slot in the sleeve *n²*, formed on the wheel around the shaft. 65

Fitting loosely on the shaft *i*, outside of the bearing *k*, is a pinion-wheel, *o*, which meshes 70 into a rack, *p*, on the standard *b*.

Keyed to the shaft *i*, at each end thereof, are the crank-arms *q q'*, at the end of which arms on the shaft are the collars *q' q²*, which are fixed on the shaft, and have inclined or sloping inner faces.

On the outer face of the pinion *o* is a projecting lug, *o'*, and a similar lug is formed on the inner face of the collar *q'*, which lugs engage with each other when the collar *q'* is thrown against the pinion and form a clutch 80 which causes the shaft *i* to be carried by the movement of the pinion in the rack. Around the shaft *i*, between the pinion *o* and collar *q'*, is a spiral spring, *i'*.

At the upper end of the standard *b* is a stop, 85 *r*, having an inclined face, which, coming in contact with the inclined face of the collar *q'*, when the shaft *i* is brought to the top of the frame *b*, gives the shaft *i* a horizontal longitudinal movement, which disengages the lugs 90 on the pinion and collar from each other. On the other standard *b'* is a sliding lug or stop-gage, *s*, which may be fixed at any desired point on the standard by a key, *s'*, the face of which stop is also inclined, so that when the shaft *i* descends the inclined face of the collar *q²*, coming in contact with the inclined face of the stop, the shaft *i* is given a longitudinal horizontal movement, which throws the lugs *o'* and *q²* into gear or contact with each other, so 95 that the pinion shall be thereby connected with the shaft.

The operation is as follows: The shank of the auger is inserted in the hollow auger-shaft

- p*, and fixed therein by the set-screws or other devices *h*, the shaft *i* being in the position shown in Fig. 1, the pinion *o* and collar *q'* being disconnected from each other, and the
- 5 auger *t* resting on the wood or other substance in which the hole is to be bored. As the crank-arms *q* are turned, causing the shafts *i* and *f* to rotate on their axes, while the pinion *o*, being mounted loosely on the shaft and being
- 10 disengaged from the collar *q'*, travels idly on the rack *p*, the auger enters the wood and the frame *c* descends until the collar *q'* comes in contact with the stop-gage *s*, the inclined face of which gives the shaft *i* a longitudinal movement, overcoming the force of the spring without moving the pinion *o* or disengaging it from the rack *p*, the pinion being held stationary by the friction between the gear-teeth, the shaft *i* sliding in the axial cavity of the
- 15 20 pinion, which movement throws the lug on the face of the collar *q'* into contact with the lug on the pinion *o*, so that when the shaft *i* revolves the lug on the collar *q'* carries the pinion with it in its revolution, and as the teeth 25 of the pinion gear in the rack the revolution of the pinion on its axis carries the frame and auger to the top of the standard *b*, where, the collar *q'* coming in contact with the stop *r*, the shaft *i* is given a longitudinal movement in
- 30 35 the reverse direction, which separates the clutch lugs and brings the shaft *i* to its former position, and a recess, *w*, formed in the face of the collar *q'*, engages with a laterally-projecting arm or lug at the top of the standard *b*, which holds the frame *e* in its elevated position. The frame is then moved to a new position. By striking or pushing the end of the shaft *i* the recess *w* is released from the lug and the auger is allowed to drop as the spring
- 40 45 *i*² carries the shaft *i* back again after the blow has been struck or the pressure is removed from the end of the shaft. The operation as described is then repeated.
- The crank-arms *q* are formed in two pieces, *v x*, one of which, on its meeting surface with the other, is provided with a projecting rib, *v'*, which fits in a corresponding groove, *x'*, on the face of the other piece, and the two pieces are

fixed at any point in relation with each other by a link, *y*, and wedge-shaped key *z*, so that 50 the arms may be lengthened or shortened, as desired.

The advantages of my improved apparatus are that the auger-shaft is automatically self-withdrawing, that it may be adjusted to bore 55 holes of any desired depth, and that augers having shanks of different lengths and sizes may be attached to and used with the apparatus.

I am aware that the use of a quadrant and 60 securing devices for the purpose of adjusting the angle of the boring apparatus is not new; and also that crank-arms formed in two pieces, so as to be adjustable, have been used before. I do not therefore desire to broadly claim the 65 same; but,

Having thus described my invention, what I claim, and desire to secure by Letters Patent, is—

1. In a boring-machine, an auger-shaft 70 hollow throughout its length, in combination with a crank-shaft geared to the auger-shaft and situated on a different vertical plane, substantially as and for the purpose specified.

2. In a boring-machine, a crank-shaft capable 75 of receiving a longitudinal as well as an axial movement, and mounted in bearings on a sliding frame, a pinion and rack, a clutch for connecting the shaft with the pinion, and devices for imparting an automatic longitudinal movement to the shaft, substantially as and for the purpose specified.

3. In a boring-machine, the combination of a crank-shaft capable of receiving a longitudinal as well as an axial movement, a pinion 85 and rack, a clutch and stops, one of which is adjustable, having inclined faces arranged to move the shaft longitudinally, so as to connect and disconnect the shaft and pinion, substantially as and for the purpose specified. 90

In testimony whereof I have hereunto set my hand this 21st day of November, A. D. 1883.

ZACHARIAH C. PHILLIPS.
